UNITED STATES PATENT OFFICE.

GARIBALDI NOCITO, OF ROSARIO, ARGENTINA.

ARRANGEMENT FOR THE BETTER EXHAUST AND USE OF THE EXPLOSION OF THE MOTOR GAS IN ORDER TO OPERATE AN ALARM BELL.

Application filed February 18, 1926, Serial No. 88,240, and in Argentina December 1, 1925.

This invention has reference generally to improvements in signalling devices and more particularly relates to a bell signalling attachment for the exhaust pipe of a motor vehicle.

It is the primary aim and object of this invention to provide a device of the above mentioned character which is designed to be interposed in an exhaust pipe and embodies 10 manually operable valve means for operating in connection with a diaphragm carrying signal so that when the valve means is actuated to partly close the exhaust the signal will be simultaneously operated to sound 15 an alarm to warn pedestrians of the approach of the vehicle.

More particularly the invention embraces the provision of a device of the above mentioned character wherein the casing is constructed so as to be fitted in exhaust pipes of various diameters while the valve chamber is formed so that the valve may be readily inserted therein.

Other objects as well as the nature, characteristic features and scope of the invention will be more readily apparent from the following description taken in connection with the accompanying drawing and pointed out in the claims.

30 The invention is clearly illustrated in the accompanying drawing, in which:—

Fig. 1 is a top plan view showing the invention applied to an exhaust pipe;

Fig. 2 is a longitudinal vertical section 35 taken on line 2—2 of Fig. 1 in the direction in which the arrows point;

Fig. 3 is a fragmentary horizontal sectional view through the arrangement, the diaphragm and the clapper being shown in 40 plan;

Fig. 4 is a perspective detail of the valve, and

Fig. 5 is a fragmentary perspective detail 45 showing a form of spring for holding the diaphragm against the aperture in the casing.

Similar characters of reference are employed in all of the above described views to indicate corresponding parts.

50 Referring now, more particularly, to the accompanying drawing there is provided a casing 1 which is preferably cylindrical and which is provided with a longitudinal bore 2 the outer surface of the body being re-

duced to form a series of step-like shoulders 55 3 for accommodating various sized exhaust pipes 4 which are adapted to be connected with the respective ends of the casing and in alignment and in connection with the bore 2.

In order to control the passage of exhaust gases through the casing in the direction indicated by the arrows in Fig. 1, suitable valve means are provided and in reducing this feature of the invention to practice the casing is provided with a cylindrical chamber 5 which is formed at right angles to the bore 2 opening from the upper surface of the casing and terminating to the opposite surface thereof. It is preferred 60 that the medial portion of the casing be square in cross-section so as to permit of the formation of the cylindrical valve chamber. Revolubly mounted in the chamber is an improved valve body 6 which includes upper 65 and lower disc-like portions 7 connected by a web 8 which is arcuate in cross-section, the substantially opposed longitudinal or vertical edges being provided with semi-circular recesses 9. Normally these recesses are 70 adapted to lie in substantial alignment with the edges of the bore 2 but upon partial rotation of the valve body in a counterclockwise direction the outer outlet end of the bore 2 is partly closed by the adjacent portion of 75 the web 8 so that some of the exhaust gases are directed through a secondary outlet 10. Disposed in front of the outlet 10 and yieldably connected to the side of the casing is 80 a diaphragm 11 which carries a suitable sounding or signalling device for instance in the form of a bell 12 and a clapper 13, the action of the gases against the diaphragm causing a shaking of the clapper 85 and a consequent sounding of the bell to 90 warn pedestrians or other motorists of the approach of the vehicle. Suitable means in the form of a spring 14 is employed for yieldably mounting the diaphragm over the opening 10.

Means for operating the valve and consequently controlling the operation of the bell preferably consists of a radially extending arm 15 connected with the upper disc 7 of the valve body, a suitable connection 16 being fastened to the outer end of the arm and operable from a point adjacent the driver's seat to rock or partially rotate the

valve body. Suitable means such as a coil contractile spring 17 has its respective ends connected to the arm 15 and the main casing 1. It is apparent that a pull on the element 16 will partially rotate the valve body 6 and upon the partial closing of the outlet end of the bore 2 some of the exhaust gases consequently pass through the secondary outlet 10 shaking the diaphragm 11 and thereby sounding the bell.

It is believed that in view of the foregoing a further detailed description of the operation of the invention is entirely unnecessary. Likewise it is believed that the advantages of the invention will be readily apparent.

Having thus fully described the invention what is claimed as new and desired to be secured by Letters Patent is:—

20 1. A signalling attachment for the exhaust pipe of a motor vehicle, including a casing provided with a longitudinal bore and a valve chamber intersecting the bore and having a secondary outlet leading therefrom, a valve rotatably mounted in the chamber for partially closing the outlet end of the main bore to allow some of the exhaust gases to pass through the secondary outlet, a diaphragm yieldably connected to the casing and positioned over the secondary outlet, and a signal carried by the dia-

phragm and adapted to be actuated by the vibration of said diaphragm.

2. A signalling attachment for the exhaust pipe of a motor vehicle, including a casing provided at the respective ends with step-like shoulders for interposition in exhaust pipes of various diameters, said casing being provided with a longitudinal bore and with a cylindrical valve chamber arranged to intersect the bore at right angles and further provided with a secondary outlet leading from the valve casing, a valve rotatably mounted in the casing including upper and lower disc-like portions, an arcuate web portion connecting the disc-like portions and in turn provided with substantially opposed arcuate recesses normally positioned in substantial alignment with the adjacent edges of the bore, manually operable and resiliently controlled means for partially rotating the valve so that the web portion of the body thereof will partially obstruct the outlet portion of the main bore and thereby deflect some of the gases through the secondary outlet which leads from the casing, a diaphragm yieldably connected to the casing and arranged over the secondary outlet, and a bell carried by the diaphragm and adapted to be actuated by the vibration of said diaphragm.

G. NOCITO.
